Primary Examiner — Paula Allen Greene(74) *Attorney, Agent, or Firm* — Andrew W. Chu; Craft Chu PLLC(57) **CLAIM**

The ornamental design for a communication device, as shown and described.

DESCRIPTION

FIG. 1 is an upper perspective view of the communication device showing my design in an assembled configuration with a back unit connected to a side unit;

FIG. 2 is a top plan view of the back unit thereof;

FIG. 3 is a bottom plan view of the back unit thereof;

FIG. 4 is a side perspective view of the back unit thereof;

FIG. 5 is an opposite side perspective view of the back unit thereof;

FIG. 6 is an end view of the back unit thereof;

FIG. 7 is an opposite end view of the back unit thereof;

FIG. 8 is a side elevation view of the back unit thereof;

FIG. 9 is a top plan view of the side unit thereof;

FIG. 10 is a bottom plan view of the side unit thereof;

FIG. 11 is a side elevation view of the side unit thereof;

FIG. 12 is an opposite side elevation view of the side unit thereof;

FIG. 13 is an end view of the side unit thereof;

FIG. 14 is an opposite end view of the side unit thereof; and,

FIG. 15 is a side perspective view of the side unit thereof. The broken lines depict environment that forms no part of the claimed design.
